UNITED STATES PATENT OFFICE.

JOHN D. REYNOLDS, OF NIOBRARA, NEBRASKA.

IRONING-BOARD.

1,206,140.

Specification of Letters Patent. Patented Nov. 28, 1916.

Application filed April 3, 1916. Serial No. 88,609.

To all whom it may concern:

Be it known that I, JOHN D. REYNOLDS, a citizen of the United States, residing at Niobrara, in the county of Knox and State 5 of Nebraska, have invented certain new and useful Improvements in Ironing-Boards, of which the following is a specification.

This invention relates to an improvement in ironing boards for laundry uses, and has 10 for its principal object to provide such a construction that the parts will be few and simple so that manufacture will be economical and that durability may be attained.

The invention has reference to an ironing board which may be readily folded to 15 occupy a very limited space, and may be conveniently extended ready for use. Also it includes certain adjustable features found to be of advantage.

With the foregoing objects in view and others to be mentioned, the invention presents a novel construction, combination and arrangement of parts, as described herein and claimed, and as illustrated in the accompanying drawing, wherein,—

Figure 1 is a view in side elevation showing the ironing board, the parts being extended. Fig. 2 is a broken away view in side elevation of the ironing board, a sleeve 30 board being added and shown in an elevated or inverted position. Fig. 3 is a plan view of the ironing board and sleeve board, the standard or prop being omitted. Fig. 4 is a view showing the ironing board when 35 folded. Fig. 5 is a broken away view of the ironing board, showing the sleeve board in a lowered position. Fig. 6 is a section on line 6 6 of Fig. 1.

Referring now to the drawing for a more 40 particular description, the device consists, in part, of an elongated, flat board 6 upon which the work of ironing may be done. It may have any suitable length and width, and as usual with ironing boards, it pref- 45 erably is formed convergent toward its free end, as indicated at *a*.

Numerals 7 indicates a table or other suitable support upon which the device may be mounted for use.

The board 6 is provided with a recess or 50 slot 8, of rectangular form, which opens on its end opposite to the convergent terminal *a*, midway between its sides or edges, and upon the bottom of the board, as indicated 55 by broken lines in Fig. 3, are secured by

any suitable means, a pair of brackets 9, each being provided with an aperture for receiving a pivot pin 10, the inner side of each bracket being disposed in line with a longitudinal wall of the slot or recess 8.

At 11 is indicated a standard or prop provided on its outer side, near its upper end, to open on its outer side with grooves, depressions or notches 12, and also provided, intermediate its ends, at longitudinal intervals, with apertures 13 to receive the pivot pin 10.

As thus described, when the board 6 and prop 11 are connected by the pin 10, the prop may have a swinging movement to 70 make contact with the bottom of the board between the pair of guide strips or elongated brackets 9, and while thus folded, the device occupies a very limited space; and for use, the parts may be readily ex- 75 tended for ironing, the prop for this purpose being disposed inclinedly with its upper end disposed in the slot or recess 8 and engaging the upper side of a projecting top *b* of the table or other suitable support, its 80 lower end resting on the floor, the inner end of the board bearing upon the lower side of the support, so that the board 6 will be disposed horizontally, the projecting ledge or edge *b* of the table being engaged in one 85 of the notches. If the table or other support has a limited height, the prop may be adjusted longitudinally with reference to its mounting, as shown in Fig. 2, wherein the ledge or leaf *b* engages in a notch 12 90 nearer to the longitudinal middle of the prop to dispose the board horizontally.

Numerals 14 indicate a pair of lugs or buffers, and provided with apertures or 95 formed as staples, and tending to prevent vibrations or lateral swinging movements of the ironing board while in use, these lugs being mounted adjacent to the inner end of said board, outwardly or transversely of the slot 8, and adapted to engage the support.

It will be seen that, since only a few parts are employed in construction, the ironing board may be manufactured at a very limited expense. It may be easily collapsed 105 or extended, or adjusted for use upon high or low supports, and since its outer end is free, it is convenient in use.

Numerals 15 indicates a sleeve board, provided at its opposed sides, near its inner end with a pair of bearing plates 16 upon 110

each of which is pivotally mounted at 17 a link 18 having a foot-piece 19 adapted to be inserted in the aperture of a lug 14, upon the bottom of the sleeve board being mounted a swivel or prop 20. The sleeve board may be disposed horizontally upon the board 6 ready for use, as shown in Fig. 5, the prop 20 bearing thereon, and may be swung upwardly, as shown in Fig. 2, when the ironing board is not in use, and as is obvious, it may be disconnected from said board, whenever desired; and when substantially the entire length of the sleeve board is required for use, the arm or prop 20 may be swung inwardly 180 degrees to the position indicated by broken lines in Fig. 5. Having fully described construction, a further explanation relating to operation is not necessary.

What I claim and desire to secure by Letters Patent is,—

A device of the type described, including a support, said support having lugs at one end, said lugs having apertures opening out through the inner ends thereof, and a sleeve-board provided upon its opposite sides, at one end, with pivoted links having foot-pieces engaging the apertures in said lugs, said sleeve-board also having a swiveled prop for engagement with said support.

In testimony whereof, I have affixed my signature in presence of two witnesses.

JOHN D. REYNOLDS.
